UNITED STATES PATENT OFFICE.

CHARLES E. WEHN, OF ALAMEDA, CALIFORNIA, ASSIGNOR TO LISTO PENCIL CORPORATION, OF ALAMEDA, CALIFORNIA, A CORPORATION OF CALIFORNIA.

PENCIL.

Application filed July 31, 1923. Serial No. 654,847.

To all whom it may concern:

Be it known that I, CHARLES E. WEHN, a citizen of the United States, residing at Alameda, county of Alameda, and State of California, have invented new and useful Improvements in Pencils, of which the following is a specification.

This invention relates to mechanical pencils and especially to improvements on the structure shown in a copending application entitled "Pencil" filed by Henry W. Larsson and Charles E. Wehn, April 21, 1920, Serial No. 375,646, patented Aug. 19, 1924, Pat. No. 1,505,452.

The object of the present invention is to generally improve and simplify the construction and operation of pencils of this character. I accomplish this object by preventing disengagement of the lead advancing rack with relation to the propelling nut, and by positively limiting the movement of the rack when fully advanced and, conversely, when completely retracted; by eliminating back lash and accidental reverse rotation of the propelling nut when the lead is extended and the pencil is in use; by providing a structure which permits ready replacement of new leads when this is desired, and by providing means for enclosing one end of the lead advancing mechanism and at the same time forming a housing or magazine for the reception of spare leads. Further objects will hereinafter appear.

One form which my invention may assume is exemplified in the following description and illustrated in the accompanying drawings, in which—

Fig. 1 is a central, vertical, longitudinal section through the pencil.

Fig. 2 is an exterior view of the pencil.

Fig. 3 is an enlarged cross section taken on line 3—3, Fig. 1.

Fig. 4 is a similar section taken on line 4—4, Fig. 1.

Fig. 5 is a perspective view of the propelling nut.

Fig. 6 is a perspective view of the housing which guides the lead advancing rod and at the same time encloses one end of the rod propelling mechanism.

Fig. 7 is a perspective view of the coupler.

Fig. 8 is a perspective view of the lead propelling rack bar.

The pencil illustrated in the present in-

stance consists of four main parts, to-wit, an upper barrel section A, a lower barrel section B, a removable lead receiving point or tip C, and a lead propelling or advancing mechanism generally indicated at D. The lead propelling mechanism as a whole consists of a coupler 2, which is perhaps best illustrated in Figs. 1 and 7. This coupler serves three functions, first, that of coupling or securing the barrel sections A and B with relation to each other; secondly, that of forming a guide for the lead propelling rack generally indicated at 3, and, third, that of supporting the lead propelling nut generally indicated at 4.

The coupler is a rod like member which is slotted from end to end, as indicated at 5, to form a guide for the rack bar indicated at 3. The center portion of the coupler is turned down to form a groove 6 as indicated at 6. The nut 4 has a length equal to the turned down portion 6 and is thereby secured against endwise movement. The nut is interiorly threaded as indicated at 8, and as such engages the teeth 9 of the rack bar 3.

The nut indicated at 4 is constructed of metal, but it is in this instance enclosed by a hexagonal shaped covering member generally indicated at 13, which is suitably secured thereto. This member has a greater length than the nut 4 and as such forms a spacer between the barrel sections A and B and, simultaneously, a closure or cover for the nut and a pair of friction members 12. The members 12 are extensions of the respective barrel sections A and B and they are slightly tapered or cone shaped as shown in Fig. 1. The ends of the cover member 13 are similarly tapered and as such cooperate with the members 12 to form frictional engaging faces to prevent turning movement of the nut in either direction, this being of considerable importance as it prevents back lash and accidental reverse turning movement of the nut when the lead is projected and the pencil is in use. The covering member is, in most instances, constructed of celluloid or like material and this is also true of the barrel sections A and B and the point C; this material being preferred as it is light and ornamental in appearance and can be cheaply worked up into the shape desired. The covering member may be secured to the nut in any

suitable manner, but actual practice shows that if the covering member is driven or pressed over the nut or shrunk thereon, satisfactory results are obtained without employing other securing means. The barrel sections A and B, as previously stated, are spaced apart by means of the covering section of the nut and they are secured with relation to the coupling member 2 in any suitable manner either by being pressed on, shrunk or otherwise secured.

The rack bar, which is best illustrated in Figs. 1 and 8, terminates in a rod 15; this rod serving the function of advancing the lead 16 from time to time as it is worn away; the advancing being accomplished by merely rotating the nut 4 in the proper direction; that is, the threads of the nut will during rotation thereof engage the teeth of the rack bar and as such will advance the rack bar and the rod 15 when rotated in one direction and will, conversely, retract the rack bar and the rod when rotated in the opposite direction. The frictional resistance imposed by the members 12 is comparatively slight and as such does not interfere with manual rotation of the nut but the friction is nevertheless sufficient to prevent accidental rotation when rotation is not intended and when the pencil is in use.

The rod 15 is positioned in direct alignment with the pencil lead indicated at 16 or the passage formed in the tip C, and it is maintained in positive alignment at all times by means of a housing member generally indicated at 17. This housing member consists of a strip of metal (see Fig. 6), which is bent upon itself to form a U-shaped clip. The outer end of the housing or clip 40 is perforated, as at 18, to form a guide for the rod 15. The clip also serves two other functions, first, that of enclosing the rod and the rack bar, and, secondly, that of forming a housing or magazine for the reception of spare leads, that is, one end of the coupler is recessed to form a chamber as indicated at 19, and the clip is forced downwardly through a central passage 20 formed in the barrel section B until the ends of the 50 clip enter the recess 19. The sides or legs of the clip when so entered lie parallel with the rack bar 3 and therefore serve as a closure or housing for the rack bar and the rod. The sides of the clip at the same time divide 55 the chamber 20 into two sections as indicated at 21 and 22 and these sections form magazine chambers into which spare leads may be inserted when the tip C is removed; the spare leads being indicated at 23. (See 60 Fig. 4.)

The tip proper is constructed as shown in Fig. 1 and preferably of the same material employed in connection with the barrel sections A and B and the covering member enclosing the nut 4. The center portion of the

tip is, however, reinforced by a threaded sleeve 24 which, at the same time, forms a passage for the reception of the leads 16 and a guide for the rod 15. The sleeve terminates in a chuck 25 which is split longitudinally as indicated at 26. A series of flexible fingers 27 are in this manner formed which serve the function of frictionally engaging the lead, thereby preventing accidental removal of the same. The inner end 75 of the tip is reduced in diameter and threaded as at 28 and the lower end of the barrel section B is, as a consequence, internally threaded to receive the same. The pencil is otherwise provided with a removable cap 30 and an eraser 31, which is normally enclosed by the cap. The usual form of eraser is employed but it is in this instance secured in a metal sleeve 32. This sleeve is threaded 80 into the upper end of the barrel section A and is in fact threaded from end to end to receive the cap 30, which is internally threaded to permit it to be screwed over the eraser and the bushing 32. This feature of the invention is, however, of no particular 85 importance as this structure may be varied or may be entirely eliminated if an eraser is not desired.

The salient features of the present invention are, first of all, the provision of a coupler which is reduced in diameter to form a bearing for the propelling nut 4 and which also serves the purpose of coupling the barrel sections; secondly, the provision of means for frictionally resisting turning movement of the nut; third, the provision of a nut such as shown in Fig. 5 which is split longitudinally as indicated at 40 to permit it to be expanded so that it may be passed over the reduced section 6, and then contracted to its original form so as to form a perfectly round nut which will properly engage the teeth of the rack bar; fourth, the provision of the clip or housing 17 which forms a closure for one end of the lead propelling mechanism and a guide therefor, and which at the same time forms two magazines for the reception of spare leads; and, fifth, the provision of means for limiting the movement of the rack bar 3 so that disengagement of the rack bar and propelling nut is prevented; this being accomplished by blanking off or extending the ends of the rack bar as indicated at 41 and 42. These extended or blanked off portions do not only limit the extreme movements of the rack bar when completely extended or retracted, but they also prevent disengagement of the nut in the rack bar.

Having thus described my invention, what I claim and desire to secure by Letters Patent is—

1. In a pencil of the character described, a rod like elongated coupling member having a longitudinally extending groove

formed therein, a non-rotatable threaded feed member slidable in the groove, a nut surrounding the coupling member and rotatable thereon and engaging the threads 5 of the feed member to impart longitudinal movement thereto, and a pair of stop members one on each end of the threaded feed member to limit longitudinal movement of the feed member and to prevent disengagement 10 of the threaded feed member and the nut.

2. A pencil comprising a pair of barrel sections, a coupling member interiorly of the barrel sections connecting the sections and 15 maintaining them in spaced longitudinal relation, said coupler having a longitudinally extending groove formed therein and an annular groove disposed at right angles thereto, a nut turnable about the coupler in the 20 annular groove and secured against longitudinal movement on the coupler by the said groove, and a non-rotatable threaded feed member extending through the nut and slidable in the first named groove and 25 adapted to be moved longitudinally by the nut.

3. A pencil comprising a pair of barrel sections, a coupling member interiorly of the barrel sections connecting the sections and 30 maintaining them in spaced longitudinal relation, said coupler having a longitudinally extending groove formed therein, a non-rotatable threaded feed member 35 slid able in the groove of the coupler, a nut surrounding the coupler and rotatable thereon and engaging the threads of the feed member to impart longitudinal movement thereto, and a pair of stop members disposed one 40 on each end of the threaded feed member to limit longitudinal movement of the feed member in either direction and to prevent disengagement of the threaded feed member and the nut.

4. In a pencil of the character described, 45 the combination with the coupler and the

longitudinally movable threaded feed member slidable therein, of a feed rod forming an extension of the threaded feed member, a pencil barrel section enclosing one end of the coupler, the threaded feed member and the feed rod, and a housing disposed interior of said barrel, said housing forming a guide for the feed rod and dividing the interior of the barrel into two lead receiving 50 magazine chambers. 55

5. In a pencil of the character described, the combination with the coupler and the barrel sections supported thereby, of a feed member longitudinally movable in the coupler, a nut surrounding the coupler and 60 engaging threads formed on the feed member, a sleeve like member enclosing the nut, a tapering friction face formed in each end of the sleeve member, and cooperating friction members formed on the adjacent ends 65 of the respective barrel sections.

6. In a pencil of the character described, a rod shaped coupler having a key-way formed therein extending from end to end, a rack bar longitudinally movable in the 70 key-way, a split nut surrounding the coupler and engaging the teeth of the rack bar, means on the coupler securing the nut against longitudinal movement and a stop member on each end of the rack bar to limit 75 the movement of the rack bar with relation to the nut and the coupler, and to prevent disengagement of the nut with relation to the teeth of the rack bar.

7. In a pencil of the character described, 80 the combination with the coupler and the barrel sections supported thereby, of a threaded feed member longitudinally movable in the coupler, a nut surrounding the coupler and engaging the threads formed on the feed member, a tapering friction face formed on each end of the nut, and cooperating friction faces carried by the coupler and engaging the adjacent ends of the nut. 85
